JOHN C. HUFFER
INVENTOR.

BY
Watson E. Coleman
ATTORNEY.

UNITED STATES PATENT OFFICE.

JOHN C. HUFFER, OF STERLING, COLORADO.

LOCKING DEVICE FOR NUTS.

1,399,862.

Specification of Letters Patent. Patented Dec. 13, 1921.

Application filed March 7, 1921. Serial No. 450,202.

To all whom it may concern:

Be it known that I, JOHN C. HUFFER, a citizen of the United States, residing at Sterling, in the county of Logan and State 5 of Colorado, have invented certain new and useful Improvements in Locking Devices for Nuts, of which the following is a specification, reference being had to the accompanying drawings.

10 This invention relates to improvements in locking devices for nuts, and more particularly to a device adapted to engage a bolt end against the head of a nut to hold the nut in position upon the bolt or to prevent 15 rotation of a bolt with relation to the member with which it has threaded engagement.

An important object of the invention is 20 to provide a device of this character which may be formed from a single piece of steel spring wire and which may be very readily applied to the bolt.

A further object of the invention is to 25 provide a lock washer comprising a coil of wire adapted to lie within the threads of a bolt and to resiliently engage therewith, the ends of the coils being extended outwardly and affording a hand-grip whereby the coil may be expanded when applying the same 30 to a bolt, the extremities of these ends being returned to engage the bolt within the threads thereof to further assist it in preventing movement of the washer.

Other objects and advantages of the invention will become apparent throughout 35 the course of the following description.

In the accompanying drawings wherein 40 for the purpose of illustration are shown preferred embodiments of my invention and wherein like reference characters designate like parts throughout,

Figure 1 is a side elevation of a bolt showing a nut lock constructed in accordance with my invention applied thereto,

45 Fig. 2 is a perspective view of a single coil lock, and

Fig. 3 is a side elevation of a multiple coil lock.

Referring now more particularly to the 50 drawings, the numeral 10 indicates a wire bent to form a coil or coils 10^a adapted to engage in the threads of a bolt 11, the coils

being made in either right hand or left hand spirals dependent upon the bolt with which they are to coact. The ends of the 55 wire are bent outwardly at the terminus of the coils to afford gripping portions 12, and again bent inwardly as indicated at 13, so that the extremities 14 thereof lie within the threads of the bolt when the coil is in normal or contracted position. In practice, the 60 points 14 are preferably sharpened, as indicated, in order that their engagement with the threads may be positive, and the interior of the coils will likewise be provided 65 with rasp-like teeth 15 directed oppositely to the direction of rotation necessary in applying the coil to the bolt.

In the use of my device the portions 12 may be engaged by the thumb and forefinger or between the jaws of a pair of pliers and move toward one another with the result that the coils 10^a are expanded, rendering the application of the washer to the bolt 11 very simple. The washer is rotated until it engages against the upper surface of the nut 16 or against the upper surface of a member through which the bolt may be threaded and the members 12 released, permitting the coils to contract so that the teeth 15 thereof engage in the metal of the bolt and the pointed extremities of the wire likewise engage therein.

From the foregoing it is believed to be 70 obvious that a locking device constructed in accordance with my invention is particularly well adapted for the use for which it is intended by reason of the fact that the application thereof to a bolt may be accomplished with a minimum expenditure of 75 labor and time and by reason of the fact that the device, after being applied, effectively locks the bolt and the member having engagement therewith against relative rotation. It will furthermore be obvious 80 that the construction as hereinabove set forth is capable of some change in modification without departing from the spirit of my invention and I accordingly do not 85 limit myself to such specific structure except as hereinafter claimed.

What I claim is:

A nut locking device comprising a single 90 length of resilient material bent to form a

spring coil having the convolutions thereof wound in the same direction as the threads of the bolt with which the device is adapted to coact, the inner faces of the convolutions of the coil being provided with bolt engaging teeth, said teeth being inclined oppositely to the direction of rotation necessary to apply the coil to the bolt, the end por-

tions of the material being formed into loops, the extremities of such end portions being sharpened and adapted to extend into the threads of the bolt.

In testimony whereof I hereunto affix my signature.

JOHN C. HUFFER.
